WINE BOTTLE RACK

Lester E. Simon, 6650 Vernon Ave. S., Minneapolis,
Minn. 55436, and James L. Phelps, 1740 Hampshire
Road, St. Paul, Minn. 55116

Filed July 17, 1974, Ser. No. 489,379

Term of patent 3½ years

Int. Cl. D6—04

U.S. CL. D6—188

FIG. 1

FIG. 2

FIG. 3

FIG. 4

FIG. 5

FIG. 1 is a side elevational view of a wine bottle rack showing our new design;

FIG. 2 is an elevational view of the side opposite that shown in FIG. 1;

FIG. 3 is an end elevational view, the opposite end being identical;

FIG. 4 is a top plan view; and

FIG. 5 is a bottom plan view.

The other end elevational view is a mirror image of FIG. 3.

We claim:

The ornamental design for a wine bottle rack, as shown and described.
